UNITED STATES PATENT OFFICE.

CHARLES SCHOLZ, OF MERCED, CALIFORNIA.

CABLE-GRIP TURN-TABLE.

SPECIFICATION forming part of Letters Patent No. 417,212, dated December 10, 1889.

Application filed April 6, 1889. Serial No. 306,235. (No model.)

To all whom it may concern:

Be it known that I, CHARLES SCHOLZ, of the city of Merced, in the county of Merced and State of California, have invented a certain 5 new and useful Cable-Grip Turn-Table, of which the following is a full, clear, and exact description, reference being had to the accompanying drawings, forming a part of this specification, and in which—

10 Figure 1 is a plan view of the entire turn-table; Fig. 2, a vertical section taken on the line *a a*, Fig. 1, and in addition showing a grip; and Fig. 3, a top view with the turn-table partly turned, and with portions broken out in order to show the anti-friction rollers.

15 Similar letters refer to similar parts throughout the several views.

A A' are the plates which form the top of the turn-table.

20 B B' are the segments forming the bed-plate.

C C' are U-shaped bars connecting the plates A A' and supporting the grip F, Fig. 2.

25 D is a tongue for holding the turn-table in position.

D' is a ring by which D may be raised.

E E' are recesses into which the tongue D drops.

F is the cable-grip in position.

30 G is a pulley upon which the cable H runs.

I I I I are stationary anti-friction rollers let into the bed-plate and upon which the turn-table rotates.

Following is the manner in which the mechanism operates. The cable H, Fig. 2, being 35 released from the grip F, the lower jaw of the grip is raised, thus closing the grip and allowing it to be run into the turn-table. It is then uncoupled from the grip-car or dummy and rests upon the bars C C'. Raising the tongue D allows the turn-table motion and it turns easily upon the anti-friction rollers I I I I. When it has completed half a revolution, the tongue D drops into E', thus 40 stopping it. The grip is then recoupled and 45 the car moved till the grip is out of the turn-table, when it may again grasp the cable.

What I claim as my invention, and desire to secure by Letters Patent, is—

A cable-grip turn-table consisting of the 50 semicircular plates A A', connected by the U-shaped bars C C', resting upon the anti-friction rollers I I I I, and provided with the locking or stopping device D E E', all substantially as set forth.

CHAS. SCHOLZ.
